[57] CLAIM

The ornamental design for a bracelet, as shown and described.

DESCRIPTION

FIG. 1 is a perspective view of an ornamental design for a bracelet showing my new design with a selected positioning of ornamental features in a bracelet with the hinges closed;

FIG. 2 is a perspective view of the design for the bracelet shown in FIG. 1 with the hinges open;

FIG. 3 is a front elevational view from one side of the bracelet of FIG. 1, showing the ornamental patterns provided.

FIG. 4 is an elevational view of the bracelet with the view from the opposite side of the view of FIG. 3;

FIG. 5 is a left elevational view of the bracelet shown in FIG. 3;

FIG. 6 is an elevational view of the bracelet with the view from the opposite side of the view of FIG. 5; and,

FIG. 7 is a top plan view of the bracelet shown in FIG. 3, the opposite view, the bottom plan view, being virtually identical.
